UNITED STATES PATENT OFFICE.

ANNIE E. GRAY, OF PHILADELPHIA, PENNSYLVANIA.

DESIGN FOR A COAT.

55,944.

Specification for Design.

Patented Aug. 3, 1920.

Application filed March 2, 1920. Serial No. 362,786. Term of patent 3½ years.

To all whom it may concern:

Be it known that I, ANNIE E. GRAY, a citizen of the United States, and a resident of Philadelphia, county of Philadelphia, and State of Pennsylvania, have invented a certain new, original, and ornamental Design for Coats, as shown in the accompanying drawings, in which—

I claim:

The ornamental design for a coat substantially as shown.

In witness whereof, I have hereunto set my hand this 12th day of January A. D. 1920.

ANNIE E. GRAY.

Witnesses:

J. STUART FREEMAN,
MERRILL T. CRAMER.
